UNITED STATES PATENT OFFICE.

MATHILDE LIND AND WERNER C. LIND, OF NEW ORLEANS, LOUISIANA.

BUTTON.

Application filed June 22, 1926. Serial No. 117,738.

Our present invention pertains to buttons, and it contemplates the provision of a simple and inexpensive device that is adapted to be readily and easily secured to a garment without

5 the employment of any skill whatsoever and without the use of thread or other fastening means.

The invention further contemplates the provision of a button that is easily attached 10 to a garment and when so attached will not casually be displaced therefrom but at the same time is adapted to be removed when desired and replaced on another garment.

Other objects of the invention will be fully 15 understood from the following description and claim when the same are read in connection with the drawings accompanying and forming part of this specification, in which—

Figure 1 is a view illustrating the two elements of our novel button in juxtaposition 20 with respect to each other.

Figure 2 is a sectional view thereof.

Figure 3 illustrates a view of the button 25 with one portion partially inserted in the other portion.

Figure 4 shows a partial sectional view with the elements fully inserted with respect to each other.

Figure 5 is a view taken in the plane indicated by the line 5—5 of Figure 3.

Figure 6 is a sectional view taken in the plane indicated by line 6—6 of Figure 4.

Figure 7 is a modified construction of 35 button.

Similar numerals of reference designate corresponding parts in all the views of the drawings.

Our novel button comprises a base portion 1 having a shank 2 and the said shank is of 40 tubular construction and arranged in one end thereof is a nib 4. The bore of the tubular portion 2 is indicated by 3. The other element of our novel button comprises a base 5 having a shank 6 and this shank terminates 45 at the end opposite the base 5 in a point through the medium of which the shank may

penetrate or pierce cloth or other material. Formed in the shank 6 is a slot 7 that terminates in an off-set 8 thereby producing a bayonet slot.

In the use of this embodiment of our invention the material to which the button is to be attached is pierced by the point of the shank 6 and the base 5 is forced into a position bearing against the material. The other 55 element of the button is then passed over the shank 6 with the nib 4 riding into the slot 7 and then the base 1 is twisted until the button 4 rests in and is locked in removable position in the offset 8.

In the modified construction of the device, the elements are identical with the exception that the shank 6 is provided with the slot 9 having the offset 10, the slot or extension of the slot 9 as indicated by 11, and the terminal offset 12. In this construction the portion 1 of the button when used is twisted so that the button passes through the offset 10, down the slot 11 and finally into the terminal offset 12. In this construction, the liability of the elements becoming disengaged 70 from the material is doubly precluded.

What we claim:

In a button, the combination of two separate members one of which is adapted to receive and engage the other in a removable manner; one of said members comprising a circular solid base portion, an integral tubular portion formed on the base portion, a nib 75 interiorly arranged on the tubular portion, the other member comprising a circular base portion and having a solid shank portion arranged thereon; said shank portion being pointed on its free end and having a channel extending from a point slightly below the 80 free end and terminating near the circular portion at an angle with respect to the shank.

In testimony whereof we have hereunto set our hands.

MATHILDE LIND.
WERNER C. LIND.
